Primary Examiner — Katherine A Holbrow(74) *Attorney, Agent, or Firm* — Patterson + Sheridan, LLP(57) **CLAIM**

The ornamental design for a display screen or portion thereof with graphical user interface as shown and described.

DESCRIPTION

The FIGURE is a front view of a display screen or portion thereof with graphical user interface, showing the new design.

The grayscale in the FIGURE indicates a contrast in appearance. The outermost broken lines in the FIGURE show an electronic device with the display screen or portion thereof. The electronic device and the display screen or portion thereof form no part of the claimed design. The other broken lines in the FIGURE show portions of the graphical user interfaces that form no part of the claimed design.
